F. HARDINGE

OIL BURNER

Filed May 16, 1921

Patented May 29, 1923.

1,456,799

UNITED STATES PATENT OFFICE.

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS.

OIL BURNER.

Application filed May 16, 1921. Serial No. 470,203.

To all whom it may concern:

Be it known that I, FRANKLIN HARDINGE, a citizen of the United States, and resident of Chicago, in the county of Cook and State 5 of Illinois, have invented a certain new and useful Improvement in Oil Burners, of which the following is a full, clear, concise, and exact description, reference being had to the accompanying drawings, forming a 10 part of this specification.

My invention relates to improvements in oil burners and is particularly concerned with oil burners of that type in which an electric motor or other similar motor actu- 15 ates means for atomizing the oil.

The objects of my invention are

First—to provide an oil burner of the character described comprising means for automatically de-energizing a motor, when- 20 ever for any reason whatever, the flame of the burner is extinguished.

Second—to provide means, such as de- 25 scribed, comprising means actuated thru the power of the motor, but controlled by the flow of unconsumed oil from the burner, and

Third—to provide means of the character described, which is simple in construction, reliable, and economical to manufacture.

Other objects will appear as this descrip- 30 tion progresses, reference being had to the accompanying drawing in which

Figure 1 is a plan view of portions of the oil burner embodying my invention,

Figure 2 is a side elevation thereof, showing certain details of my invention in elevation, portions of this figure being in section,

Figure 3 is a sectional detail taken sub- 35 stantially on line 3—3 of Figure 2, and

Figure 4 is a horizontal section taken on line 4—4 of Figure 3.

Throughout the several views similar reference characters will be used to refer to similar parts.

In my accompanying application Serial 45 No. 380,794 I have illustrated and described a furnace comprising a fire bed 5, preferably formed of fire clay, or any suitable refractory material, which is supported by a plurality of sector shaped plates 6, which incline 50 downwardly toward and rest upon the up-turned edge 7, of the annular channel 8, forming part of the conical air conduit 9. Slidably mounted within the conduit 9 is a 55 rotatable atomizing nozzle 10 driven thru a suitable gear on the shaft 11, which is in

turn driven by an electric motor 12. Oil is supplied to the burner by a pump 13, thru a pressure chamber 14 and a pipe 15.

The pump 13 is of the gear type and driven from the shaft 11 by shaft 16. 60

The details of construction of the burner thus described are clearly set forth in my aforesaid application and further reference thereto is unnecessary. In my present application I provide means for automatically de-energizing the motor 12 whenever, for any reason whatever, the flame of the burner 10 is extinguished and the oil continues to flow thru the burner. 65

This means comprises a standard switch 70 17, which is closed by pushing upon the push-button 18 and opened by pushing upon the push-button 19. The switch itself is enclosed in a suitable housing 20, one side wall of which has a thickened portion 21 in which 75 is cut a groove 22 for receiving the slide bar 23. The slide bar 23 is held in place by means of a cover plate 24 which is secured to the side of the housing by means of the screw 25 and is provided with the slot 26 80 thru which the stud 27, secured to the slide bar 23 projects. A lever 28 is pivotally mounted upon the stud 27 and is held thereon by means of the washer 29 and cotter pin 30. 85

One end of the slide bar 23 has an angularly extending portion 31 which overhangs the push-button 19 and is provided with an adjustable screw 32 which is adapted to press upon the push-button 19 and urge it 90 into position to open the switch 17 when the slide bar 23 is moved in the proper direction.

The plate 24 has two outwardly extending lugs 33 and 34 which are adapted to engage the upper edge of the lever 28 and act as limiting stops to limit the movement of the lever 28 in either direction. 95

The housing 20 is provided with two outlets 35 and 36 for conducting the conductors 37 and 38 respectively to the interior of the housing and to the switch. The conductors 37 and 38 form a part of the circuit for supplying electricity to the motor 12. 100

The channel 8 is provided with a short 105 drain pipe 40 which discharges into a hollow boss 41 extending upwardly from the bottom of the trough 42 and having an outlet opening 43 forming the side thereof. The channel 8 preferably has the edge thereof 110

2

cut away, as shown at 44, to provide an auxiliary drain in the event the drain pipe or opening 43 should become stopped up. A drain pipe 45 leads from the trough 42 and is adapted to discharge into a bucket 46 carried by one arm of the lever 28. The opposite end of the lever is provided with a counter-balance weight 47, which prevents the lever 28 from tilting until a predetermined quantity of oil has been discharged into the bucket 46. The arm of the lever 28 which carries the conduit 47 is bent at an angle to the remaining portion of the lever, as shown in Figure 2, to provide an abutment surface 49 which, when the lever 28 is rotated in a clockwise direction under the weight of the contents of the bucket 46, will be positioned directly in the path of the pin 50 carried by the shaft 16 and projecting parallel with the axis of this shaft. When this occurs the pin 50, being driven by the motor as described, will engage the end 49 of the lever and push it bodily toward the burner 10, thereby causing the stud 27 to move in the same direction in the slot 26. The stud 27 carries the slide bar 23 with it and causes the pin 32 to push the button 19 inwardly, thereby opening the switch and de-energizing the motor 12. When this happens, the pump 13 no longer operates and no oil will be supplied to the burner 10. In this manner I provide means for preventing the furnace heated by the burner, from becoming flooded with fuel oil upon the extinction of the burner flame. It should be noted that when the automatic device has been actuated to open the switch, the screw 32 will be so positioned in front of the push-button 19 that it will be impossible to start the motor until the safety device has been reset. This will prevent the starting of the motor without the safety apparatus being properly adjusted. While I have described the details of construction of the preferred embodiments of

my invention, it is to be clearly understood that my invention is not limited to these details, but is capable of other adaptations and modifications within the scope of the appended claims:

1. The combination with an oil burner comprising a rotary atomizing nozzle and a motor for rotating said nozzle of a switch for starting and stopping said motor, a slide bar having a projection for actuating said switch to stop said motor, a lever pivotally mounted upon said slide bar, a cup on one end of said lever, a counter weight on the other end of said lever for holding said cup in an elevated position, means for collecting unconsumed oil from said atomizing nozzle, means for discharging said unconsumed oil into said cup, and means, driven by said motor for engaging a portion of said lever when said cup is depressed by the weight of its contents, to actuate said slide bar to open said switch.

2. The combination with an oil burner comprising a rotary atomizing nozzle and a motor for rotating said nozzle of a movably mounted member for actuating said switch to its open position, means for collecting unconsumed oil discharged from said atomizing nozzle, and means controlled by said collected oil and actuated by said motor for moving said member to actuate said switch to its open position.

3. The combination with an oil burner having an atomizing nozzle, and a motor, of a switch for starting and stopping said motor, means for collecting unconsumed oil discharged from said nozzle, and means controlled by said unconsumed oil and actuated by said motor, for moving said switch to its open position.

In witness whereof, I hereunto subscribe my name this 11th day of May, 1921.

FRANKLIN HARDINGE.
